EX

DP 0 18,022

Design No. 18,022, dated January 24, 1888.

UNITED STATES PATENT OFFICE.

TIMOTHY J. COLLINS, OF TOLEDO, OHIO, ASSIGNOR OF TWO-THIRDS TO
JOHN R. B. RANSOM AND THADDEUS F. RANDOLPH, OF SAME PLACE.

DESIGN FOR A BARBER'S DRESSING-CASE.

SPECIFICATION forming part of Design No. 18,022, dated January 24, 1888.

Application filed December 22, 1887. Serial No. 252,768. Term of patent 3½ years.

To all whom it may concern:

Be it known that I, TIMOTHY J. COLLINS, a citizen of the United States, and a resident of Toledo, in the county of Lucas and State of

5 Ohio, have invented and produced a new and original Design for a Barber's Dressing-Case; and I do hereby declare that the following is a full, clear, and exact description of the invention, which will enable others skilled in the 10 art to which it appertains to make and use the same, reference being had to the accompanying drawing, and to the letters of reference marked thereon, which form part of this specification.

15 The drawing represents a front elevation of my newly-designed dressing-case.

The novelty of the design consists in a dressing-table having a rectangular support, B, at the right side thereof, said support having 20 compartments for towels, &c., and closed by panel-doors C, the support D of the opposite side being a panel end having an ornamental base, E, and a bracket-support, F, at the top, having a design carved in relief of the character shown, and a reeding of molding extending from thence to the inner side of the rectangular support, embellished at the point of juncture thereof by an ornamental bracket, H, the whole supporting a base-board, I, with an 25 astragal molding upon its outer edge, an upper dressing-table, K, being supported by cross-sills L, lying transversely of base-board I, and forming compartments, into which drawers M slide freely, towel-racks N, formed of a 30 single metal rod, being secured to the outer sills, L.

The table K supports an ornamental mirror-frame, O, having a base portion of a width

corresponding to the length of the dressing-table formed by supplemental side pieces, P, 40 extending to about one-third the height of the mirror-frame.

Q are shelves supported by posts R, of an ornamental design, the upper portion of the frame being suitably embellished. 45

By means of this design a narrow dressing-case is shown which has a single rectangular support provided with compartments, and such arrangement is effected without detracting from the symmetry or ornamental appearance of the dressing-case.

What I claim is—

1. In a design for a dressing-case herein described and shown, the lower part consisting of the board resting upon a rectangular support closed by panel-doors, and an opposite side supported by a panel end with ornamental base, and upper bracket support carved in relief, the whole having the ornamentation shown. 55

2. The design for a dressing-case shown and described, consisting of a rectangular support having an ornamental front, a single panel-support at the opposite side, a carved ornamentation connecting the side supports, a base-board resting upon the supports, having cross-sills, upon which rests a dressing-table provided with a mirror-frame centrally of the length of the table, as set forth. 60

In testimony that I claim the foregoing as my own I hereby affix my signature in presence of two witnesses.

TIMOTHY J. COLLINS.

Witnesses:

WILLIAM WEBSTER,
JAMES E. RAYMER.
